UNITED STATES PATENT OFFICE.

ELISHA LAWLEY McMURTRY, OF RISON, ARKANSAS.

SOLE-EDGE BURNISHER.

Application filed November 24, 1926. Serial No. 150,494.

The invention relates to improvements in machines and devices for polishing the edges of shoe soles by applying wax thereto with a heated iron, and it is one of the most important objects of the invention, to provide a new and improved burnisher which makes use of liquid wax, fed as occasion may demand, to the sole edge being burnished.

Another object is to provide an electrically heated burnisher of novel form, so constructed that a heating unit which has been burnt out, may be readily removed and a new one substituted.

Yet another aim is to provide a burnisher in which unique provision is made for removing one burnishing tip and substituting another.

Another aim is to provide a construction in which a panel for a rheostat, controlling the current to the electric heater, forms part of a casing which contains the greater part of the movable burnishing member, said casing also containing parts of the rheostat, portions of current-conducting wires, and means for conducting wax from a reservoir to a wax-conducting port of said burnishing member, a very simple and compact arrangement being thus effected, in which practically all working parts are housed and protected.

Yet another object is to provide a novel attachment for burnishing shoe soles, of such nature that it may be quickly and easily attached to a finishing machine of well known form.

With the foregoing in view, the invention resides in the novel subject matter herein-after described and claimed, the description being supplemented by the accompanying drawings.

Fig. 1 is a front elevation of a portion of a finishing machine showing a burnishing attachment connected therewith and constructed in accordance with my invention.

Fig. 2 is a transverse section on line 2—2 of Fig. 1.

Fig. 3 is a front elevation with a portion of the front casing wall removed.

Fig. 4 is a vertical section on line 4—4 of

Fig. 3.

Fig. 5 is a horizontal section on line 5—5 of Fig. 3.

Fig. 6 is a vertical sectional view on line 6—6 of Fig. 4.

Fig. 7 is a perspective view of the main body of the burnishing member.

Fig. 8 is a perspective view partly in section of the electric heater and the burnishing tip which are normally associated with the body shown in Fig. 7.

Fig. 9 is a perspective view illustrating the electric heater and the burnishing tip operatively associated with the body shown in Fig. 7 and illustrating a front plate section of the latter in readiness for application thereto.

Fig. 10 is a perspective view showing the assembled body and tip, looking toward the rear thereof.

Fig. 11 is a fragmentary front elevation showing a different means for oscillating the burnishing member.

Fig. 12 is a detail upper end view showing a different drive which may be employed for a cam which may be utilized for oscillating the burnishing member.

Fig. 13 is a small side elevation disclosing a different manner of mounting the burnisher, said burnisher having an individual stand in this disclosure, instead of being mounted upon the frame of a finishing machine.

In the drawings above briefly described, 15 designates a vertically elongated, rigidly supported casing having an opening 16 in its lower end, the front wall of said casing being preferably formed from upper and lower sections 17 and 18, secured to the body portion of the casing by screws or the like 19. The upper section 17, in the present disclosure, forms the panel of a rheostat, the swingable arm of this rheostat being disclosed at 20, its contacts at 21, and its resistance coil at 22, this coil and certain other parts such as binding posts of the rheostat, 95 being confined within the upper portion of the casing 15.

A burnishing member 23 is mounted for oscillation within the casing 15, upon an appropriate horizontal axis 24, and the lower end of said member which performs the burnishing operation, projects through the opening 16. Any desired means may be employed for oscillating this member 23.

The member 23 consists of an upper body 105 section 25 and a lower, removable section or burnishing tip 26, and these parts are preferably constructed and related as shown. The lower end of the upper section 25 has a vertical bore 27 formed therein, said bore being 110 open at its lower end but closed at its upper end. In the upper end of this bore, an in-

sulating block 28 is secured by a screw or the like 29, said block being provided with a pair of contacts 30 which are exposed at its lower end and being provided with suitable means such as the screws 31, for connecting current-conducting wires 32 and 33, with the upper ends of these contacts. In the present showing, wire 32 is electrically connected with the swingable arm 20 of the 10 rheostat, wire 33 passes out of the casing for connection with a source of current, and a companion wire 34, is connected to one of the endmost contacts 21 of said rheostat.

Removably positioned in the bore 27, under the insulating block 28, is a second insulating block 35 whose upper end is provided with contacts 36 removably engaging the contacts 30. An electric heater 37 projects downwardly from and is carried by the 20 insulating block 35 and this heater may well embody the core 38 integral with the block 35, a resistance element 39 around the core and connected with the contacts 36, insulation 40 around said resistance element, and 25 a metallic, protecting casing 41 around the insulation. This heater 37 projects downwardly through the lower portion of the bore 27, which portion is unoccupied by the blocks 28 and 35, and passes out of the open 30 lower end of the bore. Thus, if the heater should need replacing or repairing, it is an easy matter to grasp its lower end and pull it downwardly out of the bore, at which time the contacts 36 disengage from the contacts 30.

Preferably, the body section 25 of the member 23 is vertically divided in a plane between opposite sides of the bore 27, providing a front section 42, held normally in 40 place by suitable means such as screws 43. When these screws are removed, after first removing the front wall section 18 of the casing 15, access is given to the screws 29 and 31. Thus, these screws may be removed to 45 permit removal of the block 28, if any repairs or replacements should be necessary.

The burnishing tip 26 has its lower end formed with the usual groove 44 for engagement with the edge of a sole or shank, and 50 the upper end of this tip is provided with an integral attaching shank 45 of tubular form. This shank is snugly, yet removably received in the lower portion of the bore 27 and it surrounds the heater 37. When this 55 heater is as long as herein disclosed, or substantially this length, the tip 26 is also recessed for its reception, as indicated at 46. Conducting of current through the heater 37, through the instrumentality of the rheostat, will cause effective heating of the burnishing tip 26, and the extent of such heating may of course be controlled by setting the rheostat handle 20 in contact with any selected one of the contacts 21.

65 Whenever desired, the tip 26 may be

downwardly removed and another tip substituted, and for the purpose of holding any tip in operative relation with the member 23, I provide suitable means such as a spring 70 detent 47, engageable with a recess 48 in the shank 45. At its upper end, this shank may be beveled at 48' to effect release of the detent 47 when the shank 45 is upwardly forced into the bore 27.

Novel provision is made for supplying 75 liquid wax to the tip 26, of the color necessary for either tan or black shoes, or analogous shades.

In the present showing, two reservoirs 50 for liquid wax, are mounted upon the upper 80 end of the casing 15 and are connected by flexible tubes 51 (preferably metallic tubes) 85 with tubular nipples 52 which rise from the body section 25 of the burnishing member 23, said tubes 51 being within the upper 90 portion of the casing 15. The nipples 52 communicate with ports 53 formed longitudinally in the body section 25 of the burnishing member 23, and the lower ends of these ports are in communication with additional ports 54 within the tip 26, said ports 54 branching from another port 55 which opens into the groove 44 of said tip. In the present showing, the lower end of the section 25 is formed with tubular nipples 56 95 snugly, yet removably received in sockets 57 in the tip 26, so as to establish a wax-tight connection between the sections 25 and 26 of the member 23. The lower ends of the ports 53 are provided with regulating and 100 cutoff valves which may well be in the form of screws 58. By adjusting these screws as occasion may demand, the flow of wax from one or the other of the reservoirs 50 to the groove 44, may be controlled, and both of 105 these valves are closed when one tip 26 is to be removed and another substituted. Obviously, the liquid wax supplied to the tip 26 will be applied effectively by the latter to the sole and consequently the latter will be effectively burnished.

Preferably, the tip 26 is provided with a front section 26^a held in place by a screw 26^b and removable to permit cleaning of ports 54 and 55 whenever advisable.

Any desired provision may be made for lubricating all movable parts and numerous details may be resorted to in the construction of the device. The body section 25 of the member 23, is provided in the present disclosure, with bosses 59 and 60 through which the pivot 24 passes, and the latter is in the form of a screw which may be removed when the front section 18 of the casing 15 is detached, thus permitting easy removal of the 125 burnishing member 23 should this be advisable for any reason. The bosses 59 and 60 preferably abut the rear and front walls of the casing 15 respectively, and I prefer to provide stabilizing ribs 61 and 62 on the 130

member 23 and the wall section 18 respectively, the rib 61 slidably contacting with the rear wall of the casing 15, while the ribs 62 slidably engage the front side of the member 23.

Any desired oscillating means may be employed for the burnishing member 23. In Figs. 3, 4 and 5, a cam wheel 63 is provided within the casing 15, said wheel being carried by a shaft 64 which projects rearwardly from said casing, through an appropriate bearing 65 which may well be of a ball or roller type. The wheel 63 is formed with a cam groove 66 receiving a roller 67 on the member 23, so that upon rotation of said wheel, said member will be oscillated.

In Fig. 11, the member 23 is of slightly different design at its upper end, and a different type of cam 63^a is provided to move said member in one direction, a coiled, adjustable spring 68, being used to rock said member 23 in the other direction.

In Fig. 12, I have illustrated the fact that bevel gearing 69 may be employed if desired for transmitting motion to the cam shaft 70, from a right angularly disposed driven shaft 71. Other forms of means for oscillating the burnishing member 23 and other ways of driving such means, could be shown, but those herein disclosed will suffice to illustrate that I am not restricted as to such details.

For mounting the casing 15 or any suitable supporting means which might be employed in lieu of said casing, in forms of construction other than that herein disclosed, suitable provision may be made. In Figs. 1 and 2, two bracket members 72 are shown, disposed in spaced parallel planes 40 and secured at their front ends to the casing 15, while their lower ends rest upon the usual parallel, horizontally disposed tie-rods 73 of a finishing machine 74, the latter being of well known construction. The bracket members 72 are secured to the rods 73 and for this purpose I preferably employ bars 75 underlying the rods 73 and bolted at 76 to the lower ends of said bracket members. The rear ends of these bracket members may 50 jointly carry a bearing 77 for the rear end of the shaft 64, and I prefer to provide this shaft with a flanged pulley 78 driven by a belt 79 from a pulley 80 on the usual drive shaft 81 of the machine 74. If desired, a clutch (not shown) may be utilized for either connecting the pulley 80 with or disconnecting it from the shaft 81 so that the burnisher need not necessarily operate when the shaft 81 is driven to actuate other parts 55 of the finishing machine.

In Fig. 13, I have shown a special stand 83 for the casing 15 and have illustrated a driven shaft 84 carried by said stand for driving the shaft 64 or some equivalent shaft 6 of the burnisher through the instrumentality

of a belt 85 and appropriate pulleys, or other desired driving connection.

In the present showing, I have disclosed certain ways of carrying my invention into effect and while they may be followed if desired, it is to be understood that within the scope of the invention as claimed, numerous variations may be made.

I claim:

1. In a sole edge burnisher, a burnishing member composed of a main body section and an auxiliary section or burnishing tip detachably connected therewith, said sections having registering ports for conducting liquid wax to a sole edge being burnished.

2. In a sole edge burnisher, a burnishing member composed of a main body section and an auxiliary section or burnishing tip detachably connected therewith, said sections having registering ports for conducting liquid wax to a sole edge being burnished, a liquid wax reservoir from which the port of the main body section leads, and a valve for said port of the main section to close it when said burnishing tip is to be removed.

3. A structure as specified in claim 1; said sections having an interfitting nipple and socket connection at the communicating ends of their ports.

4. In a sole edge burnisher, a fixed support, a burnishing member movably supported thereby and having a port for conducting liquid wax to a sole edge being burnished, a liquid wax reservoir mounted on said support, and a flexible tube connecting said reservoir with said port.

5. In a sole edge burnisher, a vertically elongated fixedly mounted casing having an opening in its lower end, an oscillatory arm mounted in said casing and having a burnishing end projecting through said opening, said arm having a port for conducting liquid wax to a sole edge being burnished, a liquid wax reservoir mounted on the upper end of said casing, and a flexible tube in the casing connecting said reservoir with said port.

6. In a sole edge burnisher, a casing having an opening in one end, one side portion of said casing constituting a panel of a rheostat, an arm movably mounted in said casing and having a sole burnishing end projecting through said opening, and electric heating means for said burnishing end electrically connected with the aforesaid rheostat.

7. A sole edge burnisher comprising a casing having an opening in one end, an oscillatory arm mounted in said casing and having a burnishing end projecting through said opening, the other end of said arm being spaced from the other end of the casing, operatively connected rheostat parts mounted on one wall of the casing, certain of said parts being confined in the portion of the casing between said other end of the latter and said arm, and electric heating means for

125
130

said burnishing end of the arm including wiring in the casing connected with the rheostat.

8. A sole edge burnisher comprising a casing having an opening in one end, an oscillatory arm mounted in said casing and having a burnishing end projecting through said opening, the other end of said arm being spaced from the other end of the casing, operatively connected rheostat parts mounted on one wall of the casing, certain of said parts being confined in the portion of the casing between said other end of the latter and said arm, electric heating means for said burnishing end of the arm including wiring in the casing connected with the rheostat, and liquid wax feeding means for said burnishing end, including a wax reservoir mounted on the casing and a flexible tube in the casing connected with said reservoir and arm.

9. In a sole edge burnisher, a burnishing tip having a tubular attaching shank, a movably mounted body having a bore in which said shank is removably received, and an electric heater mounted in said bore and extending into said tubular shank.

10. In a sole edge burnisher, a body having a bore open at one end and closed at its other end, a stationary insulating block and means securing it in the closed end of said bore, said block having contacts and wires connected thereto, a second insulating block removably received in said bore and having contacts removably engaging those aforesaid, the outer end of said second block being inwardly spaced from the open end of the bore, an electric heater extending from said second block through the open end of the bore and having its heating element connected with said contacts of said second block, and a burnishing tip having a tubular attaching shank which is snugly received in the portion of the bore unoccupied by said blocks, said tubular shank receiving said heater.

11. A structure as specified in claim 10;

said body being divided into sections between opposed sides of the bore and having said sections detachably connected, whereby removal of one section will give access to the first named insulating block for releasing its securing means or disconnecting the aforesaid wires if it is necessary to remove this block.

12. In a sole edge burnisher, a burnishing member having a port for conducting liquid wax to a sole edge being burnished, said member being divided longitudinally of said port into sections, and means for securing said sections detachably together, the division line between said sections being disposed to give access to said port upon separation of said sections.

13. In combination with a shoe finishing machine embodying a stationary horizontal rod and a driven shaft under said rod; an attachment comprising a bracket and means securing it to said rod, a support on said bracket carrying a movably mounted burnishing member, and means for operating said burnishing member, including a rotary shaft extending from the aforesaid support and operatively connected with the above mentioned shaft.

14. In combination with a shoe finishing machine embodying a pair of parallel horizontally spaced horizontal rods and a driven shaft under said rods; an attachment comprising a pair of bracket members disposed in spaced substantially vertical planes and having means at their lower ends securing them upon said rods, a support secured to the front ends of said bracket members and carrying a movably mounted burnishing member, and means for operating said burnishing member including a rotary shaft extending from the aforesaid support and operatively connected with the above mentioned shaft.

In testimony whereof I have hereunto affixed my signature.

ELISHA LAWLEY McMURTRY.
